DESIGN FOR A PASTRY ICE CREAM CUP

Leo A. Helfgott, Brooklyn, N. Y.

Application August 7, 1934, Serial No. 52,853

Term of patent 14 years

To all whom it may concern:

Be it known that I, Leo A. Helfgott, a subject of the King of Rumania, residing at Brooklyn, in the county of Kings, State of New York, have invented a new, original, and ornamental Design for Pastry Ice Cream Cups, of which the following is a specification, reference being had to the accompanying drawing, forming a part thereof.

Fig. 1 is a perspective view of a pastry ice cream cup embodying my invention.

Fig. 2 is a top plan view of the cup illustrated in Fig. 1.

Fig. 3 is a bottom plan view of the cup illustrated in Fig. 1.

I claim:

The ornamental design for a pastry ice cream cup, as shown.

LEO A. HELFGOTT.
